UNITED STATES PATENT OFFICE.

WALTER KUNZE, OF BERLIN-WANNSEE, GERMANY.

LOUD-SPEAKER.

Application filed July 25, 1928, Serial No. 295,272, and in Germany July 30, 1927.

A type of loud speaker which gives good results is one in which a vibrating reed is operated by variations of a magnetic system or field corresponding in a measure to that of a polarized relay in which it is placed and in which it is influenced by both the flux of the permanent magnet and the alternating flux generated by the currents to be reproduced. Owing to the fact, however, that the reactions are not centralized, for the reason that the reed is supported solely from one side of the system, such a loud speaker responds most strongly to a certain frequency, that is, to a limited resonant frequency, and is subject to reproducing imperfections due to its mode of support. Attempts have been made to overcome this difficulty and to provide for the support of the reed from both sides of the field, in order to secure centralized reactions, greater intensity, a greater frequency range, and a more faithful reproduction, but, so far as I am aware, these attempts have been without practical success.

One object of my invention is to provide a loud speaker employing a vibratory reed in which the reed is supported from both sides of the magnetic system and arranged so that the reactions of the magnetic field are centralized and transmitted to the working diaphragm in such manner as to obtain a wide frequency range, and greater intensity and a much more faithful reproduction of the signals.

A further object of the invention is to provide means whereby the sensitiveness of action of the reed may be regulated and the resonant frequency of the speaker varied within desirable limits.

The invention consists of the features of construction, combination and arrangement of parts, hereinafter fully described and claimed, reference being had to the accompanying drawings, in which:—

Figure 1 is a front elevation of one form of loud speaker embodying my invention.

Figure 2 is a similar view showing a modification.

Figure 3 is a similar view showing another modification.

Figure 4 is a similar view showing still another modification.

Figure 5 is a plan view of the structure shown in Figure 4.

Figures 6 and 7 are views showing details

of construction of the device illustrated in Figures 4 and 5.

Referring now more particularly to Figure 1 of the drawing, A, A' designate a pair of superposed permanent magnets, preferably of horseshoe type, and having the pole pieces C, C' carrying the field coils D, D'. A reed B is clamped at one end at the side of the magnets opposite the pole pieces between the magnets and extends across the field space between the limbs of the magnets with its free end arranged to vibrate in the gap between the pole pieces C, C'. Extending across the field space of the magnets and secured to the limbs thereof at opposite sides of said field space is a bridge E of non-magnetic material. Centrally of the field of the magnets is arranged a stem F which couples both the reed B and the non-magnetic bridge E to the working diaphragm Q of the loud speaker, which may be of conical or other type. The stem F is threaded to receive securing and adjusting nuts f whereby the reed and the bridge are secured to the stem and whereby adjustment is afforded to regulate the position of the free end of the reed in the gap between the pole pieces to regulate the sensitiveness of action of the reed and to vary within certain degrees its resonant frequency. With this arrangement it will be seen that the reactions of the field are centralized for transmission to the working diaphragm so that a high degree of efficiency of the action of the reed is obtained to secure greater intensity of sound and a more faithful reproduction of the signals received.

In Figure 2 a modified form of the invention is shown in which there is substituted for the two field coils D, D' a single field coil H of larger size, and in which the pole piece T extending through the coil is of larger dimensions than the pole piece K. The reed L in this instance is secured at one end by a screw M to the magnets at one side and provided adjacent to its secured end with a more or less resilient offset portion M' carrying an adjusting screw M² bearing against one of the magnets whereby the position of the reed in the gap between the pole pieces may be regulated and the resistance to vibration of the reed governed. Also in this construction the non-magnetic bridge E' is rigidly secured to the magnets at one side of the field by fastening means E², while the opposite end of the bridge is free

from connection with the magnet and provided with a downturned portion E^3 carrying a set screw E^4 bearing against a magnet at the opposite side of the field whereby the 5 tension of the bridge and its resistance to vibration may be regulated. By means of these adjustment features the action of the reed may be sensitively controlled, as well as the sensitiveness of action of the bridge, 10 and the pitch and frequency of the speaker varied within determined limits.

In Figure 3 of the drawing another modified form of the device is shown in which the structure is similar to that shown in 15 Figure 1 with the omission of the lower magnet A and the pole piece C' and coil D' . The elements in this construction corresponding to those in Figure 1 are indicated by the same reference characters. This 20 construction provides a simplified type of single magnet unit which may be inexpensively manufactured and at the same time gives good results.

In Figures 4 to 7, inclusive, still another 25 modified form of the invention is shown in which a single magnet A , a pole piece C^2 and a field coil D^2 are employed. In this construction, however, the reed B' is arranged at the top of the magnet and secured at one end to one of the magnet limbs and extends at an oblique angle across the field space with its free end arranged for coaction with the pole piece C^2 . The non-magnetic bridge E^4 in this construction is 30 arranged at the base of the magnet and extends across the field space thereof and is secured at its opposite ends by fastenings E^5 to the opposite limbs of the magnet. Preferably the bridge is arranged at an 35 oblique angle so as to cross the reed, whereby a centralized coupling arrangement is provided for and the use of a comparatively long bridge obtained so that a maximum degree of efficiency is secured. In this construction of device provision is made for 40 regulating the distance between the reed and pole piece and the sensitiveness of action of the reed so that the resonant frequency may be varied. As shown, the reed B' is 45 fastened to the stem F' which is adjustable and elastically coupled to the bridge E^4 by a coiled spring F^2 . This spring is fastened at one end to the stem F' and at its opposite end is clamped by a nut F^3 to a threaded 50 regulator stem I having a flattened side or being of non-circular form and slidably and non-rotatably moveable through a similarly shaped opening I^2 in the non-magnetic bridge. The rod or stem I is in threaded 55 engagement with an adjusting sleeve J having an annular groove j engaged by the fork ends of bearing plates j' secured to the bridge whereby the sleeve is swiveled to rotate and held from longitudinal movement. 60 The sleeve J carries a knob or other operat-

ing member J' whereby it may be rotated to advance or retract the stem I and thereby compress the spring F^2 or permit it to expand, by means of which the distance between the reed and the pole piece may be 71 varied and the sensitiveness of action of the reed governed and the resonant frequency of the speaker varied within desirable limits.

Figure 5 shows a convenient way of arranging a condenser O in parallel with the magnet coils by mounting the same upon a support P of insulating material upon the unit itself.

In all the constructions disclosed it will 80 be observed that the arrangement is such as to provide for the transmission of the field reactions to the working diaphragm in the most effective manner and so that great 85 intensity and vitality of reproduction may be obtained.

What I claim is:—

1. A loudspeaker comprising means for producing a magnetic field, a vibratory reed secured at one end at one side of said field 90 and extending across the field and having its opposite end lying adjacent to the opposite side of the field, a diaphragm, and a non-magnetic element extending across and fixed to both sides of the field, said element being 95 coupled to the diaphragm and to the reed between the secured and free ends of the latter.

2. A loudspeaker comprising means for producing a magnetic field, a vibratory reed secured at one end at one side of said field 10 and extending across the field and having its opposite end lying adjacent to the opposite side of the field, means for adjusting the reed with respect to the field zone with which it 10 directly coacts, a diaphragm, and a non-magnetic element extending across and fixed to both sides of the field, said element being coupled to the diaphragm and to the reed between the secured and free ends of the 11 latter.

3. A loudspeaker comprising means for producing a magnetic field, a vibratory reed secured at one end at one side of said field and extending across the field and having 115 its opposite end lying adjacent to the opposite side of the field, a diaphragm, a non-magnetic element extending across and fixed to both sides of the field, said element being coupled to the diaphragm and to the 120 reed between the secured and free ends of the latter, and means for varying the tension of the non-magnetic element.

4. A loudspeaker comprising means for producing a magnetic field, a vibratory reed secured at one end at one side of said field and extending across the field and having its opposite end lying adjacent to the opposite side of the field, a diaphragm, a non-magnetic element extending across and fixed to 125 130

both sides of the field, said element being coupled to the diaphragm and to the reed between the secured and free ends of the latter, and means for adjusting the reed and 5 non-magnetic element to regulate the action thereof.

5. A loudspeaker comprising a permanent magnet, a reed secured at one end at one side of the magnet and having its free end vibrat- 10 ing between the pole pieces of the magnet, a diaphragm, and a non-magnetic bridge secured to the magnet at both sides thereof and coupled to the reed and the diaphragm.

6. A loudspeaker comprising a permanent 15 magnet, a reed secured at one end at one side of the magnet and having its free end vibrat- ing between the pole pieces of the magnet, means for adjusting the reed with relation to the pole pieces, a diaphragm, and a non- 20 magnetic bridge secured to the magnet at both sides thereof and coupled to the reed and to the diaphragm.

7. A loudspeaker comprising a permanent magnet, a reed secured at one end at one side of the magnet and having its free end vibrat- 25 ing between the pole pieces of the magnet, a diaphragm, a non-magnetic bridge secured to the magnet at both sides thereof and coupled to the reed and to the diaphragm, and means for varying the tension of the 30 bridge.

8. A loudspeaker comprising a permanent magnet, a reed secured at one end at one side of the magnet and having its free end vibrat- 35 ing between the pole pieces of the magnet, means for adjusting the reed with relation to the pole pieces, a diaphragm, a non-mag- 40 netic bridge secured to the magnet at both sides thereof and coupled to the reed and to the diaphragm, and means for varying the tension of the non-magnetic bridge.

In testimony whereof I affix my signature.

WALTER KUNZE.
